Charles Adams
- Sartor Patent

The Schedule referred to in that Letter Patent and making part of the same containing a description in the words of the said Charles Adams himself of his improvement in the art of constructing and manufacturing cast-
ed, forged, soldered and chain

To all persons to whom these presents shall come, Charles Adams of the City of Boston County of Suffolk and Commonwealth of Massachusetts and his
not maker sends greeting; Be it known that I the said Charles Adams have
invented a construction made and applied to near a new and useful improvement
in the art of constructing and manufacturing couches, sofas, settees and
chairs which I call the scroll-sack principle sofa, settee or chair. What I claim
as my improvement in the manufacture of the above mentioned articles
consists in the application of the scroll-sack principle in binding and hold-
ing together the parts and tightening the sackings or other material upon which
the cushion lies which affords advantages before unknown. To give a clear ill-
ustration of this it is necessary to describe the several parts in the construction
which are as follows: The several beams or rails (the front-back and end
beam or rail) are framed with sound timbers at each end so that they may
turn in the joints by a small lever, each beam or rail having at one
or both ends a nail-hole-wheel or segment of one into the tooth of which a small block
falls to hold fast what the lever gains this block is swivelled on the side of the joint
just above the nail-hole. On the upper side of the end rails are three or four short
pins with button heads around which a strong cord passes and alternately
through eyelet holes made in the ends of the sackings each end of the cord made
fast so that by turning the rails the sackings is tightened lengthwise. The front
and back edges of the sackings may be nailed fast to the front and back beam
or rail or it may be held fast on button heads and inserted into the rails and
then be tightened widthwise by turning said beams or rails. It is proper to
observe that the front rail or beam may be framed firmly into the joint so as
to not turn and the sackings tightened by turning the back rail only. By this
application

application of the windings the frames of the above mentioned articles may be kept tight and firm at all times. The seats are rendered more firm elastic and comfortable with less expense of material and labor in the stuffing than if made in the common way. The frames can be taken apart at any time and rendered capable of easy removal from place to place and through small and narrow passages. They are rendered more portable and much expense of freight may be saved when shipped in consequence of less packing and the whole article may be manufactured at less expense. In testimony that the above is a true specification of my said improvement I have hereunto set my hand and seal this first day of January in the year of our Lord one thousand eight hundred and thirty one M. W. Adams
